UNITED STATES PATENT OFFICE.

EDWIN E. SLICK, OF PITTSBURGH, PENNSYLVANIA.

BLANK SHEARING AND FORMING APPARATUS.

1,106,741.

Specification of Letters Patent. Patented Aug. 11, 1914.

Application filed May 22, 1912. Serial No. 698,882.

To all whom it may concern:

Be it known that I, EDWIN E. SLICK, a citizen of the United States, residing at Pittsburgh, in the county of Allegheny and 5 State of Pennsylvania, have invented a new and useful Blank Shearing and Forming Apparatus, of which the following is a specification.

My invention relates to apparatus for 10 shearing metal blanks which are later subjected to further finishing operations and while not restricted to such use, more particularly relates to apparatus used in cutting a multiple length blank into pieces.

15 The invention further relates to apparatus for shearing and forming substantially cylindrical blanks therefrom which are used later in making forged metal car wheels and similar articles.

20 One object of this invention is to provide a cheap and simple apparatus having novel means whereby a multiple length blank is cut into pieces forming single blanks of a predetermined length.

25 Another object of the invention is to provide apparatus having novel means whereby multiple length metal blanks are severed transversely of their axis into single blanks from opposite sides toward the longitudinal 30 axis thereof and a clean cut on the severed surfaces of the blanks is thereby obtained.

A further object of the invention is to 35 provide improved apparatus whereby multiple length blanks are severed into single blanks and single blanks of substantially cylindrical cross section are formed concurrently with the severing operations from a multiple length blank of any cross section.

40 Still further objects of my invention will appear as will be more fully disclosed in the specification and claims.

In the accompanying drawings, forming part of this specification, Figure 1 is a sectional elevation showing apparatus constructed and arranged in accordance with 45 my invention. Fig. 2 is a plan partly in section of the apparatus shown in Fig. 1. Fig. 3 is a side elevation showing the end of a multiple length blank as shaped at an 50 intermediate point in a severing and blank forming operation. Fig. 4 is an end view of the same.

In the drawings the numerals 2 and 3, 4 and 5 designate pairs of oppositely facing shear knives, the knives 2 and 3 moving vertically toward and away from each other

and the shear knives 4 and 5 advancing and retracting horizontally toward and away from each other. The shear knives are detachably secured on the ends of the pistons or plungers 6, 7, 8 and 9 which are mounted each in one of the double acting hydraulic cylinders 10, 11, 12 and 13. The opposite vertical cylinders 10, 11 and the opposite horizontal cylinders 12 and 13 are removably secured in a supporting frame 14 which is provided with feet 15 by which the apparatus is erected in place on the foundations 16.

Each of the cylinders, which are removably secured in place, is mounted on the frame 14 in the same manner, the stuffing box end of the cylinders being provided with an annular groove 17 and the adjoining portion of the frame 14 is provided with a recess 18 in which a split or sectional ring 19 is inserted. At an intermediate point in the length of the cylinders 10, 11, 12 and 13 an annular flange 20 is provided and a sectional ring 21 which is split transversely is inserted between one face of the flange 20 and the adjoining face of the frame 14 so as to secure the cylinders rigidly in position on the framework, bolts or other equivalent means are used to fasten the segmental 85 rings 21 in place.

In inserting the cylinders within the openings therefor in the frame 14 the cylinders are caused to project into the openings until the shoulders formed by the flanges 20 are 90 in engagement with the frame 14. The sections of the rings 17 are then put into position and the cylinders are then drawn outwardly so as to seat the rings 17 in the recess or groove 18 formed in the supporting 95 frame 14. The sectional rings 21, which are made of the required thickness are then inserted in place and are secured in position so that the cylinders are fastened and securely held in position in the supporting 100 frame 14.

The outer ends of the cylinders are provided with cylinder heads 22 which are secured in place on the cylinders by means of the transversely divided recessed or counter-bored rings 23, the tapering faces forming the sides of the counterbore on the inside of the rings 23, engaging the tapering faces on the cylinder flanges and cylinder heads providing means for drawing the heads into position and fastening the heads securely in position on the cylinders. The opposite or

inner ends of the cylinders are provided with bushings 24 and glands 25 which co-act to form a stuffing box for the cylinders through which the pistons or plungers project. Inlet openings 26 and 27 on the opposite ends of the cylinders provide means for admitting fluid pressure to the cylinder on opposite sides of the head of the plungers 6, 7, 8 and 9.

10 As will be seen by reference to the drawings the shear knives or cutters 2 and 3, 4 and 5 have a thin cutting edge 28 extending inwardly from one side surface thereof, and on each cutter is a semi-cylindrical recess 29, the recesses 29 in the opposite shear knives 2 and 3 or 4 and 5 when advanced into engagement with each other forming a substantially cylindrical recess extending inwardly from one face of the 20 opposing pairs of shear knives 2, 3 and 4, 5.

As shown in the drawings the concave cutting edges 28 of the vertically movable shear knives 2 and 3 are curved inwardly 25 while the cutting edges 28 of the shear knives 4 and 5 extend in a straight line although when desired the cutting edges of both pairs of knives may be concave.

30 In the operation of my improved apparatus a multiple length blank of rectangular or other cross section is placed in position between the oppositely facing pairs of shear knives. The vertically reciprocating knives 6 and 7 are then caused to advance 35 toward each other by admitting fluid pressure to the inlet ports 26 on the cylinders 10 and 11. In severing blanks from a multiple length blank which is rectangular in cross section, the multiple length blank may be 40 inserted between the shear knives with its top and bottom sides extending horizontally or it may be turned until a line through opposite corners of the blank extend vertically, (as shown by dotted lines in Fig. 1). When 45 the pistons 6 and 7 have been advanced until the adjoining edges of the knives 2 and 3 are in engagement a blank will be partly severed from the portion of the multiple length blank projecting between the cutting 50 edges of the shear knives and, simultaneously with this shearing step, the semi-cylindrical recesses in the shear knives will form and shape the projecting portion of the blank being severed into a blank of substantially semi-cylindrical cross section. The 55 knives 2 and 3 are then retracted by admitting fluid pressure to the fluid pressure inlets 27 on the other or stuffing box end of the cylinders 10 and 11, and fluid pressure 60 is then admitted to the rear end of the horizontal cylinders 12 and 13 so as to advance the pistons 8 and 9 mounted in these cylinders. When these pistons move outwardly in the cylinders the shear knives 4 and 5 approach, and the cutting edges 28 thereof en-

gage with the multiple length blank and complete the severing operation from opposite sides of the blank, the knives moving in a plane at right angles to that of the knives 2 and 3 in the first severing and shaping 70 operation. The knives 4 and 5, when provided with straight cutting edges as shown, in approaching completely sever the partly severed and formed piece from the multiple length blank and also complete the formation of the severed blank, whatever its cross section, into a substantially cylindrical blank or blank of the contour of the recesses. It should be noted that the pairs of shear knives approach the axial center from 75 each side of the multiple length blank in the cutting operations, and, in this important respect, differ from the ordinary shearing operations in which the blanks are severed by the travel of one shear knife through 80 the entire thickness or diameter of the material being sheared, and it also should be noted that the metal is forced inwardly toward its axial center by the curved or concave cutting edge of the shear knives so as 85 to prevent the formation of fins and provide a clean cut sheared surface on the blanks. The above described operations are then repeated as often as is necessary in 90 cutting a multiple length blank into the 95 desired number of single blanks. In making steel blanks for use later in forging metal car wheels the multiple length blank is heated prior to the shearing and forming operations although with other materials 100 and in making other articles the metal may or may not be so heated.

The advantages of my invention will be apparent to those skilled in the art. By means of my improved shearing apparatus 105 the blanks are cut from opposite sides toward the axial center thereof and the formation of fins on the marginal edges of the blanks is avoided and prevented. By the use of the recessed forming faces adjacent 110 to the cutting edges of the knives, blanks of any desired cross section are formed from multiple length blanks of larger size as well as those of a different cross section and blanks of a uniform size and weight are 115 formed simultaneously with the shearing operations.

Modifications in the construction and arrangement of the parts may be made without departing from my invention. Means 120 other than the hydraulic cylinders shown may be employed to actuate the shear knives. The blank forming recesses may be omitted when desired, and the shear knives formed as is indicated by the broken line on the 125 shear knife 5 in Fig. 2. But one pair of shear knives may be employed, when found necessary, the blank being turned or partly rotated after each cutting stroke in such case, and other changes may be made in 130

the construction and arrangement of the parts within the scope of the appended claims.

I claim:—

5 1. In a shear a pair of oppositely facing reciprocatory shear knives, a second pair of oppositely facing reciprocatory knives, and means for reciprocating the knives in each pair independently of the other, said knives 10 reciprocating in the same plane, at least one knife in one pair having a concave cutting edge.

2. In a shear a pair of oppositely facing reciprocatory shear knives, a second pair of 15 oppositely facing reciprocatory knives, and means for reciprocating the knives in each pair independently of the other, said knives reciprocating in the same plane, the cutting edges of at least one pair having oppositely 20 curving concave cutting edges.

3. In a shear a pair of opposed shear knives and means for reciprocating said knives toward and away from each other, and means adjacent to the cutting edges of 25 said shear knives whereby the severed pieces of metal are shaped concurrently with the cutting operation.

4. In a shear a pair of opposed shear knives and means for reciprocating said 30 knives toward and away from each other, said knives having recesses therein whereby

the severed metal is formed into a cylindrical blank concurrently with the cutting operation.

5. Apparatus for forming and shearing 35 metal blanks comprising oppositely facing pairs of reciprocatory shear knives, and means for actuating the knives in pairs, said pairs of knives reciprocating in the same plane, the opposing knives in the pairs having recesses therein whereby the metal being 40 sheared is shaped simultaneously with the cutting operations.

6. Apparatus for forming and shearing metal blanks comprising oppositely facing 45 pairs of reciprocatory shear knives, means for actuating the knives in pairs, said pairs of knives reciprocating in the same plane, the opposing knives in the pairs having recesses therein whereby the metal being 50 sheared is shaped simultaneously with the cutting operations, one pair of said knives partly severing and shaping the blanks and the other pair completing the blank severing and forming operations. 55

In testimony whereof, I have hereunto set my hand.

EDWIN E. SLICK.
